SPACER APPLYING TOOL

William N. Koeller, Birmingham, Mich., assignor to
Huck Manufacturing Company, Detroit, Mich., a corpora-
tion of Michigan

Filed Nov. 29, 1961, Ser. No. 155,775

6 Claims. (Cl. 29—227)

This invention relates to apparatus and method for assembling a coiled spacer in between a pair of spaced laminae.

The tool and method of this invention is a modification and an improvement of that shown in my copending application, Serial No. 43,452, filed July 18, 1960, now Patent No. 3,105,291, issued October 1, 1963. More specifically, the tool and method of this invention apply to the art of securing, by means of fasteners, various members to structural sandwiches of the type having relatively high strength skins or laminae spaced apart by a relatively weak, low density core. In practice, a hole is first drilled through the laminae and the core and a portion of the core surrounding the opening is removed in order to facilitate the insertion of a helically wound spacer between the laminae and internally about the periphery of the bores in the laminae. The spacer has an inside diameter substantially the same as the diameter of the bores through the laminae. The outside diameter is greater, of course, and, hence, reinforces axially the area radially proximate to the bores. By so axially reinforcing the area around the bores, various structure can be secured to the sandwich by means of a fastener extending through the hole; in other words, the spacer prevents the sandwich from axially collapsing. In order to provide for a relatively uniform bearing surface between the helically wound spacer and the internal surfaces of the spaced laminae, the ends of the coil are feathered or machined relatively flat. These ends are also bent axially outwardly in order to facilitate the initiation of the insertion of the spacer within either of the bores. These ends are relatively weak and can be easily distorted, thereby preventing the proper insertion of the coil within the hole.

In applications in which the sandwich is comprised of laminae of relatively heavy gauge, some difficulty has been met in utilizing present apparatus and methods in that there is a tendency to bend or distort the feathered ends of the coils upon insertion. This same effect also occurs when laminae of conventional thickness are used and a coil of a relatively small wire diameter is used. It is an object, then, of this invention to provide a method and apparatus for installing a coiled spacer between a pair of spaced laminae without distorting the end coils thereof.

It is another object of this invention to provide apparatus and a method for inserting a coiled spacer in between a pair of spaced laminae.

It is an object of this invention to provide a method and apparatus for the insertion of a coiled spacer of the above described type in between a pair of spaced laminae being of a heavy gauge relative to the wire diameter of the coil without permanent distortion or damage to the coil.

Other objects, features, and advantages of the present invention will become apparent from the subsequent description and the appended claims, taken in conjunction with the accompanying drawings, in which:

FIGURE 1 is a sectional view of a structural sandwich having a spacer assembled therein and a fastener, of lockbolt type, secured to the sandwich;

FIGURE 2 is an elevational view of the spacer applying tool of this invention shown in a position for initially inserting a spacer in the sandwich structure;

2

FIGURE 3 is an elevational view of the tool of this invention shown in a position for completing the assembly of the spacer with the sandwich structure, and illustrating a moved position of the tool in broken lines;

FIGURE 4 is a transverse sectional view of the structure shown in FIGURE 3 looking substantially along the line 4—4; and

FIGURE 5 is an enlarged sectional view of the structure shown in FIGURE 3 looking substantially along the line 5—5.

Looking now to the drawings, a tool embodying the features of this invention is generally indicated by the numeral 10 and comprises an elongated shaft 12 having a knurled handle 14 on one end thereof. The handle 14 is provided with circumferentially disposed longitudinally extending serrations at its tapered inner end 16. The opposite end of the shaft 12 terminates in a reduced diameter portion 18, having a diameter relative to the diameter of the shaft 12 of a preselected size to form thereby a shoulder 19. The tool 10 is designed for inserting a spring-like helically wound spacer 24 in a sandwich structure 26 which consists of spaced ends or laminate 28 and 30 which, for convenience of description, are hereinafter referred to as the "near" and "far" laminae 28 and 30 which, for convenience of description, are separated by a low density reinforcing core material 32 which may be formed of a plastic material or a very thin gauge metal and serves the purpose of strengthening the sandwich assembly 26.

As previously discussed, it is desirable to secure various structure along the various portions of the sandwich by means of conventional fastening devices. In the assembly of an angled structure 36 to the sandwich structure 26 by means of a fastener, such as a lockbolt 34 (FIGURE 1) which consists of a pin 35 having a collar 37 swaged into locking engagement therewith, it is necessary to first assemble the spacer 24 within the sandwich structure 26 in order to prevent crushing of the core material 32 and, hence, to prevent permanent deformation of the laminae 28 and 30. Thus, a hole is first drilled through the sandwich structure 26, thereby forming openings or bores 39 and 41 in the laminae 28 and 30, respectively, and an opening through the corresponding core material 32. Next, the core material surrounding the drilled opening is removed to a predetermined increased diameter to form a cavity 38 by the use of a suitable tool such as that shown in the copending application of Harold G. Brilmyer, Serial No. 423,327, filed July 12, 1960. The helically wound spacer 24 is in the shape of a coil spring and has an inner diameter at least equal to the diameter of the openings 39 and 41 such as to permit the insertion of the pin 35 therethrough. Since the spacer 24 has an outside diameter greater than the diameter of the openings or bores 39 and 41 and less than the diameter of the cavity 38, the spacer 24, when located within the cavity 38, provides axial support for the area of the laminae 28 and 30 radially proximate to the bores 39 and 41 and also for the low density core material 32 in that area. In the assembled condition, the coils of the spacer 24 are maintained axially solid, with adjacent coils being in contact with each other, for providing thereby a total axial length substantially equal to the spacing between the laminae 28 and 30 with the result that the axial load on a fastener such as the lockbolt 34 is reacted by the laminae 28 and 30 and the spacer 24, hence preventing the crushing of the low density core material 32.

In the use of the tool 10 to assemble the spacer 24 within the cavity 38 in the sandwich structure 26, the spacer 24 is mounted on the shaft 12 with the serrations 16 in engagement with one end 42 of the spacer 24. The shaft 12 is extended through the bores 39 and 41 and the

cavity 38 until the opposite end 44 of the spacer 24 is in engagement with the near lamina 28. The tool 10 is then rotatably manipulated such that the end 44 of the spacer 24 is threaded through the opening 39 in the lamina 28. Hand pressure is exerted axially on the handle 14 concurrently with the rotation of the handle to thereby urge the spring member or spacer 24 into the bore 39. Note that, as the handle 14 is rotated, the serrations 16 engage the end 42 of the spacer 24 and several of the adjacent coils of the spacer 24 in order to thereby urge the spacer 24 to rotate with the handle 14. In practice, three coils from the end 44 of the spacer 24 are initially inserted into the cavity 38 to prevent damage to the feathered end during the remainder of the installation which is to be described.

When the spacer 24 has been partially inserted through the bore 39 so that a plurality of coils of the spacer 24 at the end 44 thereof have been positioned between the laminae 28 and 39, the tool 10 is then completely withdrawn from the sandwich 26 and from the spacer 24 and the shaft 12 is inserted from the opposite end of the structure 26 through the bore 41 in the far lamina 30 into the cavity 38 (FIGURE 3) such that the shoulder 19, defined by the reduced diameter portion 18 and the end of the shaft 12, is in engagement with the inner side of the lamina 28 and the reduced diameter portion 18 is in engagement with the surface of the lamina 28 defining the bore 39 (FIGURE 4). This engagement of the shoulder 19 and of the reduced diameter portion 18 with the lamina 28 positively locates the tool 10 in operative position for further threading of the spacer 24 into the structural sandwich 26. With the tool 10 located such that the shoulder 19 of shaft 12 bears against the lamina 28 in the manner described, the shaft 12 is then tilted or angled into contact with the surface of the far lamina 30 defining the bore 41 (FIGURE 3). The handle 14 is rotated in a direction causing it to progressively pull the spacer through the opening or bore 39 in the lamina 28 such that the spacer 24 is continuously threaded into the sandwich structure 26 and into the cavity 38 between the spaced laminae 28 and 30. As can best be seen in FIGURES 3 and 5, the portion of the shaft 12 adjacent to the reduced diameter portion 18 engages those coils which are located within the cavity 38 between the laminae 28 and 30 such that rotation of the tool 10 in the proper direction exerts a force upon these coils which pulls the successive and remaining coils of the spacer 24 into the cavity 38. Note that, as the last coil located at the end 42 of the spacer 24 is being drawn into the cavity 38, the force of insertion is applied, not against that feathered portion, but rather against the plurality of coils already inserted within the space between the laminae 28 and 30, hence providing for the insertion of the coil 24 without distortion or damage.

To describe the above action more specifically, the handle 14 is first physically rotated in one direction to initially thread the spacer 24 partially through the bore 39 into the cavity 38. Next, upon insertion of the shaft 12 of the tool 10 into the cavity 38 from the opposite or far lamina 30, as previously described, the handle 14 is then swung or rotated to define a frusto-conical path about the axis of the bores 39 and 41 while maintaining contact between the shoulder 19 and the inner surface of the lamina 28 and maintaining contact between the reduced diameter portion 18 and the surface defining the bore 39 in the lamina 28; at the same time, the end portion of the shaft 12 adjacent the reduced diameter portion 18 is in engagement with those coils of the spacer member 24 which have been inserted within the cavity 38 and bears against the spacer 24 such that, as the handle 14 is swung in its frusto-conical path, the spacer member 24 is progressively pulled within the cavity 38. Note that the shaft 12 is free to roll about the periphery of the bore 39 in the lamina 30 while the reduced diameter portion 18 is free to roll about the periphery of the bore 41 in the lamina

28. It can thus be seen that the spacer 24 and the tool 10 are rotated about the axis of the bores 39 and 41 in one direction until the spacer 24 is partially threaded through the bore 39 in the lamina 28, and then the tool 10, after being inserted into the cavity 38 from the opposite side of the sandwich 26, is rotated in a generally conical path about the axis of the bores 39 and 41 in an opposite direction, thereby causing the spacer 24 to be moved completely into the cavity 38.

10. Note, then, that with a tool 10 constructed as described, means are provided for effectively and efficiently inserting a coil type spacer 24 between a pair of spaced laminae 28 and 30 without resultant injury to the feathered end portions thereof. By providing the tool 10 with the reduced diameter portion 18, effective guide means are provided whereby the motion of the tool 10 in the insertion of the spacer 24 is controlled. Without some means to effectively control the swinging of that end of the shaft 12 of the tool 10, it would be possible for the spacer to be severely distorted by being moved too far within the cavity 38 such as to actually damage the spacer 24 and, hence, destroy its effectiveness.

15. The shaft 12 is of a diameter just slightly smaller than the diameter of the bores 39 and 41 such that the maximum gap possible between the shaft 12 and the bore 41 in the far lamina 30 is less than the wire diameter of the coils of the spacer 24. Thus another function is served in that, upon location of the tool 10 for installation of a spacer 24, only a slight gap exists between the bore 41 in the far lamina 30 and between the shaft 12. Thus, any tendency for the spacer 24 to be threaded out through the far lamina 30 as it is being installed is prevented. Note that the axial length of the reduced diameter portion 18 is selected such as to not extend into those coils 20 of the spacer 24 which are yet to be drawn into the cavity 38.

25. While it will be apparent that the preferred embodiment of the invention disclosed is well calculated to fulfill the objects above stated, it will be appreciated that the invention is susceptible to modification, variation and change without departing from the proper scope or fair meaning of the subjoined claims.

30. What is claimed is:

1. For use with a sandwich-like structure comprising a pair of spaced laminae having coaxial openings therethrough, a tool for inserting a spring-like spacer coaxially with the openings and in between the spaced laminae comprising an elongated shaft having a handle at one end and a reduced diameter portion extending axially from that end of said shaft opposite from said one end and defining a generally flat, continuous shoulder for engaging the peripheral surface of the openings.

45. 2. For use with a sandwich-like structure comprising a pair of spaced laminae having coaxial openings therethrough, a tool for inserting a spring-like spacer coaxially with the openings and in between the spaced laminae comprising an elongated shaft having a handle at one end and a reduced diameter portion extending a preselected distance axially from that end of said shaft opposite from said one end and defining a generally flat, continuous shoulder for engaging the peripheral surface of the openings.

50. 3. For use with a sandwich-like structure comprising a pair of spaced laminae having coaxial openings therethrough, a tool for inserting a coil spring-like spacer coaxially with the openings and in between the spaced laminae comprising an elongated shaft having a preselected diameter relative to the openings such that the maximum gap possible between said shaft and the openings is less than the wire diameter of the spacer, said shaft having a handle at one end and a reduced diameter portion extending axially from that end of said shaft opposite from said one end and defining a generally flat, continuous shoulder for engaging the peripheral surface of the openings.

4. For use with a sandwich-like structure comprising a pair of spaced laminae having coaxial openings therethrough, a tool for inserting a coil spring-like spacer coaxially with the openings and in between the spaced laminae comprising an elongated shaft having a preselected diameter relative to the openings such that the maximum gap possible between said shaft and the openings is less than the wire diameter of the spacer, said shaft having a handle at one end and a reduced diameter portion extending a preselected distance axially from that end of said shaft opposite from said one end and defining a generally flat, continuous shoulder for engaging the peripheral surface of the openings.

5. For use with a sandwich-like structure comprising a pair of spaced laminae having coaxial openings therethrough, a tool for inserting a coil spring-like spacer coaxially with the openings and in between the spaced laminae comprising an elongated shaft having a preselected diameter relative to the openings such that the maximum gap possible between said shaft and the openings is less than the wire diameter of the spacer, said shaft having a handle at one end and a reduced diameter portion extending a preselected distance axially from that end of said shaft opposite from said one end and defining a generally flat, continuous shoulder for engaging the peripheral surface of the openings, said handle terminating in a circumferentially extending, longitudinally serrated tapered portion adjacent said one end of said shaft.

6. For use with a sandwich-like structure comprising a pair of spaced laminae having coaxial openings therethrough, a tool for inserting a coil spring-like spacer coaxially with the openings and in between the spaced laminae comprising an elongated shaft having a preselected diameter relative to the openings such that the maximum gap possible between said shaft and the openings is less than the wire diameter of the spacer, said shaft having a reduced diameter portion extending axially from one end a preselected distance and defining a generally flat, continuous shoulder for engaging the peripheral surface of the openings.
